CLAIM

The ornamental design for electric scooter frame, as shown and described.

DESCRIPTION

FIG. 1 is a top, front and right side perspective view of an electric scooter frame showing my new design;
FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, front and right side perspective view of the electric scooter frame, shown in use.
The broken lines in the drawings illustrate the portions of the electric scooter frame, which form no part of the claimed design.

The broken line showing of a bike in FIG. 9 depicts environmental subject matter and forms no part of the claimed design.

1 Claim, 9 Drawing Sheets
